POWER NAIL DRIVING TOOL

John L. Ollig, Reuben V. Miller, and Marvin E. Hirsch, Winsted, Minn., and James M. Westerholm, Seattle, Wash., assignors, by mesne assignments, to First Bank of Grantsburg

Application August 23, 1956, Serial No. 605,777

1 Claim. (Cl. 1-46)

This invention relates to power nail driving tools by which a multiplicity of nails may be successively fed and driven into the work.

This application is a continuation-in-part of our co-pending application, Serial Number 530,514, filed August 25, 1955.

As in our co-pending application, it is an object to provide an efficient and simplified nail-driving tool which may be readily and conveniently employed with a minimum of skill and effort on the part of an operator and which may be quickly and easily loaded without jamming and which is positive in action without reliance upon gravity feed and is adapted to be used at any convenient angle and in relatively inaccessible corners and places where manual hammering is impractical.

While utilizing the main features and principles of our earlier invention, our new nail-hammering tool provides a somewhat simplified and even more highly efficient feeding mechanism which is automatic in operation and which positively prevents any danger of the jamming of nails even through inadvertence on the part of the operator.

Another feature of this invention is the provision of a simplified and highly improved nail-holding magazine and its cooperative relationship with the feeding mechanism of the tool.

Still another feature is the provision through cooperation of essential parts, of a substantially shortened nail-ing tool and a better balance of weight of the various parts thereof to facilitate handling and operation.

These and other objects and advantages of our invention will more fully appear from the following description made in connection with the accompanying drawings wherein like reference characters refer to similar parts throughout the views and in which:

Fig. 1 is a view mostly in side elevation with some portions broken away to show interior parts of our improved power nail-driving tool, showing a nail in the last stages of being driven in a piece of work, the door of the magazine being shown in dotted lines when swung to full open position;

Fig. 2 is a side view of our improved device wherein the rear and lower portion of the structure is shown in side elevation and wherein most of the view is taken in vertical section taken substantially axially of the barrel and feeding sleeve, in this view the barrel of the tool being fully protracted;

Fig. 3 is a front elevation taken from the muzzle of the device with the nail detached, as indicated by the line 3-3 of Fig. 1;

Fig. 4 is a fragmentary side elevation showing the forward portion of the barrel with slots accommodating leaf spring nail-centering means;

Fig. 5 is a front elevation of the tool showing a nail held in the centering means at the forward end of the barrel;

Fig. 6 is a longitudinal section taken substantially on

2

the line 6-6 of Fig. 5 and showing the nail-receiving and centering device;

Fig. 7 is a bottom plan view of the forward portion of the feeding sleeve and the barrel (with the magazine removed) and with important nail-guiding elements appearing in full;

Fig. 8 is a cross section on a larger scale taken on the line 8-8 of Fig. 2;

Fig. 9 is a detail sectional view on an enlarged scale 10 showing the structure of the torsion spring means for actuating the nail-advancing dog;

Fig. 10 is a detail axial section taken on a larger scale 15 illustrating the structure of a knob and retaining element for cooperation with the nail-advancing dog in the magazine; and

Fig. 11 is a side elevation illustrating one embodiment 20 of a form of nail clip or tier of interbonded nails.

Referring now to our improved nail-hammering tool, a combined housing and handle member 13 is disposed 25 intermediate of the ends of the tool and serves to rigidly support a forwardly extending exterior feeding sleeve 14, the rear end of which is threadedly attached as shown, to the interiorly threaded housing portion of member 13 at 14a. A locking nut 15 is applied forwardly of said 30 housing and forcibly screwed against the forward surface of the same. The combined handle and housing 13 has a rigid laterally extending pistol grip 13a with an appropriately positioned slidable trigger 13b conveniently mounted for manipulation by the forefinger of the 35 user. At the rear of the combined handle and housing member 13 and axially with the feed sleeve 14, a short cylinder 16 is rigidly supported, being internally threaded within the housing portion of member 13 and provided with a locking collar 16a which is jammed against the rear face of the housing portion. As shown in the drawings, Figs. 1 and 2, the pistol grip handle 13a extends laterally and medially of the ends of the gun, balancing the weight thereof to facilitate handling and operation.

40 A source of reciprocating power such as a pneumatic, electric or other motor, is supported from the housing and handle member 13 and in the embodiment of the invention illustrated, is disposed at the rear of member 13 for more effectively producing a counterbalancing of the parts of the overall tool to facilitate portability and handling thereof in operation.

In the embodiment shown, the source of reciprocating power is a conventional type of pneumatic hammer such as is made by Skil Corporation of Chicago, Illinois, with some rearrangement of airports and valves to mount and house the hammer of the power source and most of the ports, valves and passages rearwardly of handle and mounting member 13 and to thereby foreshorten the forwardly projecting length of the tool from the handle. 50 To this end, a fitting 17 is secured to the outer extremity of handle pistol grip 13a and is adapted to be connected by a flexible hose with a strong source of pneumatic pressure which may be obtained from a compressor or analogous device. Fitting 17 communicates with an upwardly extending air passage, not shown, which is controlled by a valve operated through slidable retraction of the trigger member 13b. The released air passes rearwardly through the upper portion of the handle through a fitting 18a, a horizontal pipe 18 and into a 55 chamber 19a formed laterally at one side of a header casting 19. Header 19 has the conventional passages therein of pneumatic hammer mechanism of the class described and is generally of cylindrical cross section, the forward end being rigidly connected to the rear end 60 of the cylinder 16 by a heavy snap ring 20 and connection collar. Projecting forwardly from the front end of the casting 19 and into the rearward portion of cylinder 65

16 is an axially disposed, relatively short reciprocating hammer P constituting a conventional part of the pneumatic mechanism. This hammer P in its retracted position is spaced a short distance, preferably within a range of from three to four inches from the rear end 22a of an elongated nail-hammering rod 22 which extends axially through the housing portion of the combined housing and handle member 13 and also axially through the feeding sleeve 14.

The forward portion of hammering rod is slidably and smoothly received with close working clearance, within a tubular barrel 23 which in turn is slidably mounted within the forward portion of sleeve 14 for smooth reciprocation of the sleeve and barrel, in the operation of the tool.

The nail-hammering rod 22 is actuated and urged to retracted position by means of a forwardly tapered or bee-hive type of coil spring 24 which is anchored in its rear convolutions to the forward portion of cylinder 16 and which at its forward portion surrounds and engages a shoulder 22a formed by an enlargement at the rear portion of the hammer rod 22 which enlargement extends for a few inches terminating rearwardly in the abutment previously described which is spaced a short distance forwardly of the forward end of the reciprocating hammer P.

The barrel 23 is urged forwardly to protracted position relative to sleeve 14 by suitable means such as an elongated coil spring 25 surrounding loosely the nail-hammering rod 22 and having its rear end abutted against a shoulder 14b provided near the rear extremity of feed sleeve 14 while its forward end is abutted against the rear extremity of the barrel 23. Thus, the barrel 23 is protracted until the forward end thereof is pressed by manipulation of the handle 13a against the work where the nailing is to be accomplished.

Efficient slide means are provided for guiding the barrel 23 in its longitudinal sliding and reciprocation within sleeve 14. To this end, as shown in Figs. 8 and 2 and 3, a straight longitudinal slot 26 is cut through one side of sleeve 14 (the top, as shown in Fig. 2) and a second similar slot 27 is longitudinally formed at the side of sleeve 14 (see Fig. 8), said slots terminating in abutments afforded by the stock of the sleeve to precisely limit forward and rearward movement of the barrel within the sleeve. Narrow slide blocks 28 and 29 respectively work in the slots 26 and 27 and are rigidly affixed to the barrel 23 and to a semi-cylindrical saddle member 30a by suitable means such as the threaded bolts 31. Thus, the saddle 30a slides relative sleeve 14 along with the barrel 23 with which it is rigidly connected.

Saddle 30a constitutes the upper and connection portion of nail-magazine-frame 30 which extends laterally from the barrel 23 and sleeve 14 in the general central plane of the pistol grip 13a. The magazine frame 30 and its connector saddle 30a, are preferably reinforced by two or more reinforcing ribs 30b (see Fig. 3) which extend transversely of feed sleeve 14 and merge into the general exterior surfaces of the frame. On the inner surface of the frame 30, a laterally extending curved guiding rib 30c is provided, disposed in rather close spaced relation to the rear flange 30d of the plate which acts as a closure for the rear of the magazine. The spaced relation of rib 30c and flange 30d confines the heads of a tier of nails arranged in a predetermined relation, as illustrated in Figs. 2 and 11 and as will be more fully described in detail. Additional ribs 30e are preferably provided having smooth surfaces at the same elevation as the bearing surface of rib 30c for engaging the shank portions of a series of nails in the overlapping head formation illustrated.

A magazine door and side plate 32 is hinged along its forward edge to the rigid forward flange 30f of the magazine frame, being of similar configuration to the frame 30 and carrying at its free edge a spring retainer clip 32a

which is adapted to engage and secure with the rear flange 30d of the magazine frame. The door plate 32 at its inner and outer edges relatively to sleeve 14 and at its free edge is flanged for reinforcement and to afford accommodating depth. At the interior outer edge, as shown in Fig. 1, the door is further reinforced by a bar 33 which also projects slightly to interengage the flange at the outer edge of the magazine frame 30 and thereby, to precisely align the opposing flange edges of the two parts

10 forming the magazine body. A nail-advancing-dog 34 is swingably mounted within the confines of the magazine, in the embodiment shown, being attached and pivoted upon the inward, forward corner of the inside of door plate 32 and being urged inwardly relative to sleeve

15 14 by suitable means such as a spirally arranged spring 35 (see Fig. 9) having its inner end anchored to a fixed pivot post 34a and having its outer end provided with a detent which abuts against a short post provided by a cylindrical housing 36 to which the arm of dog 34 is fixed.

20 Nail-advancing dog 34 as shown, has an enlarged head 34b which is adapted as illustrated in Fig. 2 to engage the medial portion of a series of nails preferably in clip formation, to normally urge the same inwardly towards a nail-receiving slot S, formed appropriately longitudinally in sleeve 14 and located adjacent to the forward end of said sleeve.

25 To facilitate outward swinging of the nail-advancing dog 34 and to retain the same in full open position for nail-loading, we provide a knob and retaining mechanism, illustrated in detail in Fig. 10. In the form shown, this mechanism comprises a rigid pin 37 affixed to the head 34b of the dog and extending perpendicularly to said head, and through an arcuate slot 32c, appropriately formed in the door plate 32 of the magazine, and extending concentrically of the cylindrical housing 36 of dog 34.

30 Said pin 37 at its enlarged inner portion is slidably surrounded by a spring-pressed retaining sleeve and knob 38 and has attached as by a screw 39 to its outer extremity, a small disc 37a of somewhat larger diameter than the reduced outer portion 37b of the pin. Knob-sleeve 38 slidably engages disc 37a and is urged inwardly against the outer face of magazine-door plate 32 by such means as a coil spring 39 abutted at its outer end against disc 37a and abutted at its inner end against an interior annular flange 38a which surrounds medially the reduced portion 37b of the pin. The enlarged inner portion of the pin 37 slides smoothly in slot 32c and said slot at its outer end terminates in an enlarged circular recess 32d which is of a diameter to accommodate the knob sleeve 38, the sleeve being pressed inwardly by spring 39 when dog 34

35 is swung fully outwardly through the medium of the knob sleeve, thereby retaining dog 34 in full open position for loading of the magazine.

40 45 50

55 A multiplicity of nails N for selective feeding and subsequent hammering, are arranged preferably in a peculiar tier formation as illustrated in Figs. 2 and 11. As shown, the nails of a series lie in a common general plane with the successive heads of the nails from outermost position, inwardly relative to the nail magazine and feeding sleeve 14 overlapping, heads being abutted against

60 shanks of the adjacent outwardly disposed nail and the tip portions of the nails being substantially abutted, as clearly shown. Thus, the series of nails in tier formation converge from their heads to their tips and in the magazine as described, are in most compact form, and furthermore, through such convergence and their advancement inwardly impelled by dog 34 and guided by arcuate rib 30c, present the innermost nail longitudinally of the nail-receiving slot S in feeding sleeve 14 and in a slightly inclined relation to said slot and sleeve for subsequent feeding and guiding by telescoping movement of sleeve 14 over barrel 23 rather than through conduits, passages or channels disposed exteriorly of the sleeve.

65 70 75 Efficient mechanism is provided for feeding and guiding said nails forwardly and longitudinally of the barrel;

for ultimately in the cycle of operation projecting a nail within the barrel to a position to be driven and for preventing positively jamming of successive nails in the feeding and hammering operations as well as in inadvertent release of the tool during pressure-applied hammering operation before a nail is fully driven into place. Such mechanism comprises a number of closely related cooperating parts which will now be described. To assist in the understanding of the function of said parts, we would first state assuming the magazine loaded, whenever the barrel 23 is fully protracted forwardly of sleeve 14, a nail (usually the innermost nail of the nail clip) is positioned in the receiving slot S of sleeve 14 because of inward urging on the part of nail-advancing dog 34 (see Fig. 2). Thereafter, longitudinal movement of the sleeve 14 with the muzzle of the barrel 23 abutted against the work causes the sleeve 14 to telescope over the barrel 23, first forwardly moving with sleeve 14 the forward end of the nail-rod 22 until said end pushes the nail N-1 in Fig. 2 into centering means 45 within the forward end of the barrel and thereafter through very rapid hammering strokes and with application of further pressure longitudinally of the gun, causing the nail to be fully driven into the work.

At the same time that the foregoing hammering operation occurs, sleeve 14 moves forwardly relative to the barrel 23 and an abutment S-2 at the rear end of the nail-receiving slot S forces the then innermost nail forwardly through certain guide slots and passages longitudinally disposed of the sleeve and in sleeve and barrel, until the preceding nail is fully driven, whereupon the second nail passes through a longitudinal communication passage X in the lower side of the forward portion of the barrel as viewed in Figs. 1 and 2, being disposed then below and in contact with the forward portion of the reciprocating hammer rod 22, as shown in Fig. 1. Thereafter, as feeding sleeve 14 and the combined mounting and handle 13 are retracted longitudinally and rearwardly away from the work, the second nail is moved from its position shown in Fig. 1 into the position of the nail N-1 of Fig. 2, ready for the next hammering operation, and is moved inwardly within the axial portion of the barrel by a multi-function spring-pressed dog 46, which is pivoted to the magazine frame 30.

Referring now to Fig. 7 which is a bottom plan view of the feeding sleeve and barrel (with the magazine, saddle 30a and of course, dog 46 removed and with the barrel fully protracted or extended), it will be seen that the nail-receiving slot S is a little longer than the length of nails utilized; extends through the forward end of sleeve 14 and has a nail-head-receiving enlargement S-1 at the rear end thereof, partially defined by a nail-head-abutment S-2 which in forward movement of the sleeve 14 relative to the barrel, pushes a nail forwardly, ordinarily stripping the same from the inward end of the magazine.

The longitudinal, communication passage X in the forward portion of the barrel is longitudinally aligned with nail-receiving slot S; is shaped in conformity to the configuration of the nails utilized with adequate clearance laterally and end-wise and includes the nail-head-receiving aperture X-1 at the rear portion thereof together with an extension passage or slot X-2 extending rearwardly of the opening X-1 and longitudinally aligned with slots X and S. The height of slot S (thickness of the slotted portion of sleeve 14) is slightly greater than the maximum diameter of the head of the nails utilized.

Rearwardly of the sleeve-nail-receiving slot S and the sharp nail-head abutment S-2, sleeve 14 is provided with a longitudinal nail-guiding and camming rib S-3 longitudinally aligned with slot S and preferably having a length slightly greater than the length of the nails utilized. A rearwardly inclined camming surface S-4 merges into the sharp nail-abutment S-2 at its forward portion and

is slightly contoured concavely to properly guide the head of a nail in vertical alignment with the camming rib S-3.

The cooperative functioning of the camming rib S-3, 5 sleeve-nail-receiving slot S and the nail-advancing mechanism of the magazine is very important to prevent jamming of an imprisoned nail N-2 (see Fig. 1) in the event that through inadvertence of the operator, a 10 first nail N-1 is only partially driven into the work when the tool is pulled away from the work with a second nail N-2 (see Fig. 1) disposed partially within the barrel below and in contact with the reciprocating hammer rod 22. In such event withdrawal of the tool from the work through the influence of protracting spring 15 25, causes sleeve 14 to move rearwardly relative to the barrel 23 and to the nail magazine affixed thereto. In such rearward movement of sleeve 14, the imprisoned nail N-2 in nail receiving slot S (see Figs. 1 and 2) is in aligned relationship with the normal, innermost position 20 of the nails in the clip of the magazine. The camming rib S-3 in such rearward movement of the sleeve 14 relative to barrel 23 produces an outward pressure against the top nail N of the clip of nails in magazine 30, thereby providing space for return of the nail N-2 in Fig. 1, if 25 such inadvertence in withdrawal of the tool occurs on the part of the operator.

From the foregoing explanation of the close cooperating parts and structure of our device, it will be seen that no jamming of nails in ordinary and proper operation of 30 the tool is possible but even in the case of inadvertence on the part of an operator in prematurely withdrawing the tool from the work before completing the hammering operation, an imprisoned nail in the slot S of the feeding sleeve cannot be jammed with the innermost nail 35 of the magazine.

Brief reference has been made to the nail-centering mechanism at the outer end of the barrel 23. As illustrated in Figs. 4 to 6, inclusive, a satisfactory mechanism comprises a pair of leaf spring members 45 anchored 40 at their rearward ends by suitable screws 41 within slotted portions 23a of the barrel. These slotted portions inwardly define inclined spring-engaging surfaces 42 which limit inward movement of the springs and assist in guiding the same. The leaf springs 45 at their 45 forward ends are contoured to a cross sectional shape 45a of semi-circular configuration and cooperate as clearly shown in Fig. 6, to center and receive the point and forward shank of a nail axially of the barrel 23.

The multifunction nail-guiding and actuating dog 46 50 is swingably mounted on a pivot screw 46a passing through the rearward end of the dog and being affixed to the magazine frame 30 at the rearward end thereof. Pivot screw 46a is disposed adjacent the dispensing end of the nail magazine and medially of the width thereof, as clearly shown in Figs. 1 and 2. The inward and working surface of dog 46 is gradually curved from the pivoted end to the free end thereof. Dog 46 is urged inwardly by suitable means such as the spiraled leaf spring 47 applying pressure against the outer surface of 55 the dog at a point eccentrically of and forwardly of the pivot 46a. Inward movement of dog 46 is limited by a pair of transversely aligned projections 46b which engage the outward longitudinal shoulders provided through the nail passage X in the barrel.

60 Our nailing hammering tool is by no means limited for use with an interbonded clip of nails, as is illustrated in one form in Fig. 11. Nevertheless, it is particularly well adapted and closely cooperates with the overlapped head-tier relationship of nails whether bonded into clips or loosely arranged within the magazine.

As shown in Fig. 11, a multiplicity of nails arranged in tier formation as previously described, are interbonded by suitable frangible material such as certain 70 of the plastics or by thin coatings of soft or weak metals.

Thermosetting plastics may be used and such metals as lead alloys, commercial solder materials and rod materials commercially utilized in metal spraying may be employed, sprayed or applicator-applied to one or more zones extending transversely of the held and arranged tier of nails. As shown in Fig. 11, a transverse zone of the bonding material is applied to the shanks adjacent the pointed ends and a second zone of bonding material is applied to a zone spaced forwardly some distance from the overlapped heads. As many as 25 nails may be included in each clip and the magazine comprising frame 30 and plate 32 may be of such length as to accommodate several clips. The successive innermost nails of the utilized clip are successively and positively stripped off of the remaining nails in the magazine during successive operations of the tool with the abutment stripper S-2 at the rear of the nail-receiving slot S, positively engaging the head of a nail and moving the same forwardly as the forward end of the barrel is pushed against the work, telescoping the sleeve 14 over barrel 23.

The forward portion of frame 30 is affixed to the barrel by a metal plate 43 having an outward shank portion 43a which is rigidly secured against the inner surface of the frame 30 of the magazine. Plate 43 has a relatively wide barrel-attaching portion 43b which extends through the open nail passage X and is welded as indicated in Fig. 3 to the sides of the barrel defining passage X.

Operation

The functions of most of the cooperating parts have been described previously in conjunction with the preceding description.

To load the magazine, the nail-advancing, dog arm 34 is swung downwardly by grasping knob handle 38 on the exterior of magazine door plate 32, sliding it outwardly in the arcuate slot 32c until it has reached extreme position in the enlargement recess 32d where the spring 39 automatically locks the dog. Magazine door 32 may then be readily swung to open position, giving complete access to the interior of the magazine and nails are loaded in the magazine frame 30 with the heads thereof disposed in the groove G defined between rib 30c and the rear flange 30d of the magazine frame with the nails pushed to innermost position relative to sleeve 14. The door 32 may then be closed and retained by spring clip 32a and the sleeve knob 38 pulled outwardly, releasing the sleeve from aperture 32d whereafter the spiral spring 35 urges the dog arm inwardly against the loaded nails.

The barrel 23 of our nailing tool is normally protracted outwardly by the coil spring 25 with the parts then positioned as shown in Fig. 2.

The reciprocating piston P provided by the conventional pneumatic mechanism or motor-driven mechanism is purposely spaced in its retracted position several inches rearwardly of the retracted position of the hammering rod 22, as shown in Fig. 2. This is to enable top forward momentum of piston P to be achieved before impacting the rear extension 22b of the hammering rod. The hammering rod 22 is reciprocated only through a short stroke, for example between $\frac{3}{8}$ and $\frac{5}{8}$ of an inch.

In utilizing the tool, the entire weight thereof may be supported from one hand of the operator by the pistol grip handle 13a and the tool may be directed downwardly, upwardly or obliquely, as desired and may be applied in restricted corners and places where manual hammering is practically impossible.

In power-hammering, the tool is advanced longitudinally against the work with the muzzle of barrel 23 pressed perpendicularly against the surface of the work to be nailed. For structural jobs, crating, etc., it is often desirable to provide the extremity of barrel 23 with circumferentially arranged serrations or teeth 23t to engage

the work and eliminate slipping of the barrel until driving is begun, but this is entirely an elective feature.

As previously recited, longitudinal forward movement of the tool causes sleeve 14 to telescope over the barrel 23, the magazine of course having always a fixed relation to the barrel since it is secured thereto and slides in the sleeve through the slide mechanism illustrated in detail in Fig. 8. The positive stripping of a nail by the abutment S-2 at the rear end of the nail-receiving slot S in the forward portion of sleeve 14 has been described in detail. It is positive in action and with the cooperation of the extension passage and groove X-2 in the barrel, the nailing passage X and nail-head-receiving opening X-1 causes a second nail to be forced by dog 46 into the interior of the barrel when the tool is again moved away from the work and the barrel fully protracted through action of the coil spring 25. In connection with the stripping and guiding of the nails N successively from the series, the peculiar arrangement of the overlapping heads of the nails with the converging of the nails forwardly towards their points, causes the innermost nail to be inclined slightly in an inward direction, as clearly shown in Fig. 2, thereby aiding in a cleancut stripping action.

In Fig. 1, the nail N-1 is shown almost fully driven to place with the second nail N-2 riding beneath the then reciprocating hammering rod 22 and urged against the hammering rod by dog 46. If the operator inadvertently withdraws the tool from the work thinking the hammering completed, which is very unusual, the centering springs 45a release from engagement with nail N-1 and its head (leaving the nail in the work), nail N-2 still being imprisoned within the nail-receiving slot S at the forward portion of sleeve 14.

As the tool continues to be withdrawn from the work, sleeve 14 retracts relatively to the barrel whereby upon full withdrawal the magazine frame 30 affixed to the barrel is ultimately positioned in the at rest position relative to the nail-receiving slot S of the sleeve, as shown in Fig. 2. In such movement, the slightly protruding curved camming surface S-3 affixed to the sleeve just rearwardly of the nail-receiving slot presses on the innermost nail, thereby providing space for accommodating the imprisoned nail N-2 when the barrel is fully protracted to the position shown in Fig. 2. Thus, there is no possibility of the head of nail N-2 jamming against the forward point of the innermost nail of the magazine even when the operator is inadvertent in his withdrawal of the tool from the work.

In conjunction with the relative movement of the nail imprisoned in nail-receiving slot S of the sleeve, it is desirable to provide the barrel just rearwardly of the nail-receiving-opening X with the extension groove X-2 which serves to guide the forward end of the nail in inclined relation upwardly and thereafter, to receive and guide the head of the imprisoned nail until the barrel is fully retracted with the head of the nail aligned with opening X-1 and whereafter dog 46 accomplishes its second function as shown in Fig. 2, by pushing the nail bodily inward through the nail passage X into the barrel.

From the foregoing description it will be seen that we have provided an improved, simplified and highly efficient power nail-driving tool of very compact shape and structure and wherein the successive feeding of nails is all internal in the structure as contrasted with prior art devices where outwardly or laterally projecting conduits or feeding mechanism is required, furnishing obstruction and clumsiness and for the most part, often resulting in jamming of successive nails. The nails in our tool are positively stripped off, imprisoned and moved forwardly of the barrel and then into the barrel through the internally disposed, cooperating guiding and feeding elements.

As has been described, nails are fed without any assistance from gravity and are automatically delivered in

position for hammering within the forward portion of the barrel without any possibility of successive nails jamming even through inadvertence on the part of the operator.

Closely cooperating with nail-feeding and guiding mechanism, we provide a novel and highly efficient, readily accessible magazine which is adapted to employ loose nails disposed in a predetermined tier arrangement and which is particularly well adapted for supplying nails from a bonded clip or plurality of bonded clips.

It will of course be understood that various changes may be made in the form, details, arrangement and proportions of the parts without departing from the scope of our invention.

What is claimed is:

In a power nail-driving device, a tubular barrel, a nail-feeding sleeve slidably mounted on said barrel and surrounding the same, means for urging said sleeve to retracted position relative to said barrel with said barrel being extended beyond the forward end of said sleeve when the device is in rest position, an elongated hammer rod axially mounted within said barrel for independent reciprocating movement therein, a nail magazine extending laterally of said barrel and supported therefrom and having an open inner nail delivery end in juxtaposition **25** to the exterior of said sleeve, means within said magazine for urging a series of nails arranged in tier formation toward said nail delivery end and inwardly relative to said sleeve, said sleeve having a longitudinal nail-receiving slot therein registering with the nail delivery end of said magazine when said sleeve is fully retracted relative to said barrel, said opening being defined at its rear end by an abutment for engaging and stripping off the innermost nail from the said magazine during movement of said sleeve relative to said barrel, a longitudinal nail passage formed in said barrel and longitudinally aligned with said nail-receiving slot of said sleeve and disposed forwardly thereof, and a resiliently mounted guide dog in said barrel passage for urging a confined nail inwardly for ultimate axial position in said barrel ahead of said hammer rod.

- 5** to the exterior of said sleeve, means within said magazine for urging a series of nails arranged in tier formation toward said nail delivery end and inwardly relative to said sleeve, said sleeve having a longitudinal nail-receiving slot therein registering with the nail delivery end of said magazine when said sleeve is fully retracted relative to said barrel, said opening being defined at its rear end by an abutment for engaging and stripping off the innermost nail from the said magazine during movement of said sleeve relative to said barrel, a longitudinal nail passage formed in said barrel and longitudinally aligned with said nail-receiving slot of said sleeve and disposed forwardly thereof, and a resiliently mounted guide dog in said barrel passage for urging a confined nail inwardly for ultimate axial position in said barrel ahead of said hammer rod.
